UNITED STATES PATENT OFFICE.

PETAR M. BULATOVICH, OF SESSER, ILLINOIS.

RAILWAY-SPIKE.

1,228,291.

Specification of Letters Patent.

Patented May 29, 1917.

Application filed August 28, 1916. Serial No. 117,359.

To all whom it may concern:

Be it known that I, PETAR M. BULATOVICH, a citizen of the United States, residing at Sesser, in the county of Franklin and State of Illinois, have invented new and useful Improvements in Railway-Spikes, of which the following is a specification.

The present invention relates to improvements in the construction of spikes primarily designed to be inserted in railway ties to have the heads thereof engage with the base flanges of the rails upon the tie, and the object of the invention is to produce a spike having means whereby the same will effectively engage with the wood of the tie to hold itself firmly in position when driven to within the tie.

In the drawing:

Figure 1 is a sectional view through a rail and a portion of a tie illustrating a portion of the improvement, and

Fig. 2 is a perspective view of the spike.

Referring now to the drawing in detail, 25 1 designates the rail, 2 the tie upon which the rail rests and 3 the spike which is adapted to be driven into the tie and to have its head engage with the base flange of the rail 1.

Copies of this patent may be obtained for five cents each, by addressing the "Commissioner of Patents, Washington, D. C."

If desired the underface of the head 4 30 of the spike 3 may be serrated, as illustrated in the drawings, and the shank of the spike is inclined from two of its opposite sides to its end providing the same with an entering point 5. The point 5 from adjacent the straight sides of the shank is 35 serrated longitudinally for a predetermined distance to provide outer comparatively thin limbs 6 and 7, and a central comparatively thick limb 8. The limbs 6 and 7 40 when the spike is driven into the tie contacting with the fiber of the latter will spread away from the central limb 8 and as a result the spike is effectively held 45 against removal.

What I claim is:—

A railroad spike comprising a shank having a tapered penetrating end which is slotted longitudinally a predetermined distance in a line with the straight sides of 50 said end of the spike, whereby to produce outer comparatively thin limbs or members and an inner comparatively thick limb or member, as and for the purpose set forth.

In testimony whereof I affix my signature.

PETAR M. BULATOVICH.
